[57] CLAIM

The ornamental design for a base for a telephone set, substantially as shown and described.

DESCRIPTION

FIG. 1 is a top front isometric view of a base for a telephone set showing our new design;

FIG. 2 is a top plan view thereof;

FIG. 3 is a front elevational view thereof;

FIG. 4 is a right side elevation thereof;

FIG. 5 is a left side elevation thereof;

FIG. 6 is a top front isometric view of a second modified embodiment of the telephone base illustrated in FIG. 1;

FIG. 7 is a top plan view thereof;

FIG. 8 is a front elevation thereof;

FIG. 9 is a right side elevation thereof;

FIG. 10 is a left side elevation thereof;

FIG. 11 is a top front isometric view of a third modified embodiment of the telephone base illustrated in FIG. 1;

FIG. 12 is a top plan view thereof;

FIG. 13 is a front elevation thereof;

FIG. 14 is a right side elevation thereof;

FIG. 15 is a left side elevation thereof;

FIG. 16 is a top front isometric view of a fourth embodiment of the telephone base illustrated in FIG. 1;

FIG. 17 is a top plan view thereof;

FIG. 18 is a front elevation thereof;

FIG. 19 is a right side elevation thereof;

FIG. 20 is a left side elevation thereof;

FIG. 21 is a bottom elevation view common to all embodiments; and

FIG. 22 is a rear elevation view common to all embodiments.

In the figures the broken lines representing the handset are shown for illustrative purposes only.
